United States Rubber Company, New York, N.Y., a
corporation of New Jersey

Filed June 25, 1965, Ser. No. 85,901

Term of patent 14 years

(Cl. D90—20)

Fig. 1

Fig. 2

Fig. 3

FIG. 1 is a perspective view of a tire embodying my new design, it being understood that the full line portion is repeated throughout the circumference of the tire, shown by means of broken lines.

FIG. 2 is an enlarged fragmentary elevational view of the full line portion shown in FIG. 1, and

FIG. 3 is a fragmentary sectional view taken substantially on the plane indicated by line III-III of FIG. 2.

The dominant features of my design reside in those portions shown in full lines in the drawings.

I claim:

The ornamental design for a tire, substantially as shown and described.
